UNITED STATES PATENT OFFICE.

GEORGE W. KELLER, CHARLES BRASSINGTON, ABRAHAM BRASSINGTON, AND HARRY D. KOSTENBAUDER, OF ARISTES, PENNSYLVANIA.

COAL-WASHING JIG.

1,041,800.

Specification of Letters Patent.

Patented Oct. 22, 1912.

Application filed January 4, 1912. Serial No. 669,322.

To all whom it may concern:

Be it known that we, GEORGE W. KELLER, CHARLES BRASSINGTON, ABRAHAM BRASSINGTON, and HARRY D. KOSTENBAUDER, citizens of the United States, residing at Aristes, in the county of Columbia and State of Pennsylvania, have invented certain new and useful Improvements in Coal-Washing Jigs, of which the following is a specification, reference being had to the accompanying drawings.

This invention relates to certain new and useful improvements in coal washing jigs and has for its primary object to provide new and improved means for agitating the jig cradle whereby the coal is separated from the heavier particles of slate.

Another and more specific object of the invention resides in the provision of a jig cradle mounted for vertical and longitudinal bodily movement, and means whereby a greater vertical movement of the cradle is obtained at one end thereof than at the other end.

25 A further object of the invention is to provide improved means for adjustably mounting the cradle whereby its discharge end may be disposed out of the plane of the opposite end thereof to facilitate the movement of the body of coal through the cradle in a longitudinal direction, the adjustment of the cradle also simultaneously varying the extent of longitudinal and vertical movement of the cradle.

30 35 A still further object of the invention is to provide a comparatively simple, efficient and inexpensive operating means for jig cradles whereby the coal may be quickly and thoroughly separated from the slate and other foreign matter contained therein.

40 With the above and other objects in view, the invention consists of the novel features of construction, combination and arrangement of parts hereinafter fully described and claimed, and illustrated in the accompanying drawings in which—

Figure 1 is a side elevation of a coal washing jig, one side of the water tank being broken away to show the cradle arranged therein; Fig. 2 is a top plan view; Fig. 3 is a longitudinal section taken on the line 3—3 of Fig. 2; Fig. 4 is a transverse section taken on the line 4—4 of Fig. 3; Fig. 5 is a detail side elevation of one end of the cradle illustrating the adjustable mounting of the same

whereby the variable direction of thrust or throw of the cradle is obtained; and Fig. 6 is a detail perspective view of the cradle supporting bracket which is more particularly designed for use at the rear end 60 thereof.

Referring in detail to the drawings 5 designates a tank upon the opposite side walls of which a transverse shaft 6 is journaled at its ends in the bearings 7. A belt wheel 8 65 is centrally fixed upon this shaft and is traversed by the driving belt 9 which extends from any suitable source of power. The inner walls of the tank 5 are lined with metal plates 10, and the end walls 11 are preferably inclined inwardly and downwardly to the bottom 12 of the tank. Within the upper portion of the tank 5 the jig cradle 13 is arranged. This cradle is suspended or hung in the tank from the transverse shafts 14 70 and 15 which are mounted in the bearings 16 and 17 respectively arranged upon the side walls of the tank above the front and rear ends of the cradle 13.

The cradle 13 consists of the parallel side 80 walls 18, the inner surfaces of which are lined with the metal plates 19. The rear end of the cradle is closed by the transversely extending plate 20, and the lower portion of the front end of the cradle is also closed by 85 the transverse plate 22 which is provided upon its upper edge with an outwardly extending lip 23 to closely engage the bottom wall of the hopper 25 which is formed upon the lower end of an inclined channelled 90 guide 24. The side plates 19 of the cradle at the front ends thereof are provided with extensions 26 which are extended into the inner sides of the hopper 25. A conveyer 27 is mounted in the guide 24 and in the 95 hopper 25, said hopper being disposed adjacent the outlet end of the cradle. As the particular means of mounting this conveyer forms no part of the present invention, the same will not be described in detail. The 100 bottom of the cradle 13 consists of a plurality of perforated metal plates 28 which are arranged between the side walls of the hopper and held thereon in any desired manner. The bottom of the cradle at its 105 front end is provided with the usual discharge gate 29 which is pivotally mounted in the side walls 18 as indicated at 30. The side plates 19 of the walls 18 of the cradle are provided with depending flanges or 110

wings 31 upon their front ends to prevent material moving off of the ends of the gate 29 when the same is disposed below the walls of the cradle. To the ends of the gate at 5 its free edge the lower ends of the bars 32 are pivotally connected, the upper ends of said bars being pivoted to the forward ends of the weighted arms 33 fulcrumed upon the standards 34 which are fixed to the side 10 walls 18 of the cradle.

Upon the side walls of the jig cradle 13 and at the front end thereof a transverse shaft 35 is rigidly held at its ends in the bearings 36. To this shaft 35 the forward 15 ends of the arms 37 are loosely connected, the rear ends of said arms being connected in a similar manner to the transverse shaft 14 mounted upon the jig tank. The rear end of the cradle 13 is also supported by a 20 pair of arms 38, the upper ends of which are mounted upon the shaft 15, the lower ends thereof being connected to the journaled blocks 39 upon the walls of the cradle by means of the journals 40. Upon the 25 shaft 6 the eccentrics 41 are keyed or otherwise rigidly fixed, and upon these eccentrics the upper ends of the cradle actuating arms 42 are mounted, the lower ends of said arms being journaled upon the shaft 35 arranged 30 upon the front end of the cradle walls. It will be observed from reference to Fig. 3 that the front arms 37 are of greater length than the rear cradle supporting arms 38. The former are disposed at an angle of 35 about 15° with relation to the longitudinal plane of the cradle while the latter arms are disposed at an angle of about 30° with relation thereto. It will thus be obvious that upon the oscillatory movement which is 40 transmitted to the cradle by the arms 42 in the rotation of the operating shaft 6, there will be a greater vertical movement of the front end of the cradle than of its rear end. By mounting the cradle for movement in this 45 manner, it will also be readily seen that the water will force its way through the openings in the bottom wall of the cradle and through the bed of material therein, and exert its greatest pressure upon the material 50 in the forward portion of the cradle so that the complete separation of the coal from the foreign materials is effected at its point of discharge. When the coal is lifted by the water and floated over the front end wall of 55 the cradle and into the hopper 25, the slate and other particles of heavy foreign material move down the inclined bottom wall 28 of the cradle when the same is in its lowermost position, such inclination of the cradle 60 being effected by the greater vertical movement of the cradle at its front end as above explained. When sufficient slate has accumulated upon the gate 29 to overcome the weighted arms 33, said gate opens and 65 disposes the material in the bottom of the jig

tank, as is common in machines of this character now known in the art. A second inclined conveyer 43 is provided to remove this foreign material from the bottom of the tank. A valve of any suitable form indicated at 44 is also preferably provided at the bottom of the jig tank to draw off the minute particles of coal and dust which find their way through the openings in the bottom 28 of the cradle.

In order to provide means for varying the direction of greatest movement of the jig cradle which is desirable in the separation of different grades of coal, the bearings for the stationary shaft 14 above the front end of the cradle are preferably adjustable, said bearings being mounted upon the brackets 45. These brackets are rigidly fixed upon the walls of the jig tank and are provided with the upwardly inclined portions 46, said inclined portions of the brackets being formed with a plurality of openings 47 to receive the fastening bolts for the bearings 16. By moving these bearings upwardly or downwardly upon the inclined arms 46 of the brackets 45, the degree of angularity of the arms 37 with relation to the cradle may be increased or decreased as desired so that the greater portion of the thrust exerted by the arms 42 upon the cradle may be in a 95 vertical or longitudinal plane.

In Fig. 6 we have shown a bracket 45' which is provided with an arm 46' extending at right angles to the secured arm of the bracket above the walls of the jig tank. This bracket is particularly designed for use in connection with the rear cradle supporting arms 38 and permits of the vertical adjustment of the upper ends of said arms so that the cradle may be disposed at any desired longitudinal inclination within the jig tank. This latter form of bracket may, however, also be employed in connection with the forward arms 37 so as to adjust the angular disposition of said arms with relation to the jig cradle and thus vary the extent of vertical movement of the forward end of the cradle.

Within the cradle 13 and between the side walls thereof at its rear end, a suitable feed gate 48 is arranged, and the bottom of the cradle is preferably provided with an inclined or stepped portion 49, to facilitate the movement of the material into the forward portion of the cradle after it has 115 passed beneath said gate.

From the foregoing it is believed that the construction and operation of our improved coal washing jig will be fully understood. The above described means for hanging or 125 suspending the movable cradle within the jig tank greatly facilitates the washing or separation of the coal from the slate and also assures its thorough separation owing to the fact that the greatest impact or pres- 130

sure of the water upon the bed of material is at the forward or discharge end of the 5 cradle. In jigs of this character with which we are familiar, no means is provided for simultaneously and inversely varying the vertical and longitudinal movement of the cradle so as to maintain a proper compound reciprocating action thereof for the separation of various materials of different 10 specific gravities. By means of our invention we aim to overcome this deficiency and obtain a quick and thorough separation of the coal from the foreign matter. The device consists of comparatively few elements 15 which are simple and durable in construction and may be manufactured at comparatively small cost.

While we have shown and described the preferred construction and arrangement of 20 the various parts, it will be understood that the invention is susceptible of considerable modification without departing from the essential feature or sacrificing any of the advantages thereof.

25 Having thus described the invention what is claimed is:—

1. The combination with a jig tank and a cradle to reciprocate therein, of supporting arms connected at one of their ends to the 30 cradle, inclined supports mounted upon the jig tank, a transverse shaft, the other ends of said arms being fixed to the shaft, bearings for the shaft longitudinally adjustable upon said supports, inclined hanger 35 arms connected to said cradle and adjustable on the jig tank independently of said first named arms to vary their inclination with relation to the cradle, and means for actuating the cradle.

40 2. The combination with a jig tank and a cradle to reciprocate therein, of supporting arms connected to one end of the cradle, a transverse shaft, the other ends of said arms being fixed to said shaft, obliquely movable 45 bearings for the shaft mounted upon the jig tank, means for rigidly securing said bearings in their adjusted positions, inclined hanger arms connected to the other end of

the cradle, bracket plates mounted on the jig tank, and means for adjusting said arms 50 upon the bracket plates to vary their inclination with relation to the cradle, and means for actuating the cradle.

3. The combination with a jig tank and a cradle to reciprocate therein, of supporting arms connected to one end of said cradle, a transverse shaft, said arms being fixed upon the shaft, longitudinally inclined supports mounted upon the walls of the tank, adjustable bearings for the ends of said 60 shaft longitudinally movable on the supports, inclined hanger arms connected to the other end of said cradle, and means for mounting said arms upon the jig tank and vertically adjusting the same to vary their inclination 65 with relation to the cradle, and means for actuating said cradle.

4. The combination with a jig tank and a cradle to reciprocate therein, of a transverse shaft mounted in one end of the cradle, 70 supporting arms loosely connected to said shaft, inclined supports mounted upon the walls of the jig tank, bearings longitudinally adjustable upon the inclined surfaces of said supports, a shaft rotatably mounted at its 75 ends in said bearings, the other ends of the cradle supporting arms being fixed upon said shaft, a transverse shaft mounted upon the jig tank, inclined hanger arms loosely mounted upon said shaft and connected to 80 the cradle, and means for vertically adjusting said transverse shaft to vary the inclination of the arms with relation to the cradle, and actuating means connected to the shaft mounted in the end of the cradle. 85

In testimony whereof we hereunto affix our signatures in the presence of two witnesses.
